United States Patent Office.

DAVID DE HAVEN, OF NEW ORLEANS, LOUISIANA.

Letters Patent No. 105,436, dated July 19, 1870.

IMPROVEMENT IN STEERING APPARATUS.

The Schedule referred to in these Letters Patent and making part of the same

To all whom it may concern:

Be it known that I, DAVID DE HAVEN, of New Orleans, in the parish of Orleans and State of Louisiana, have invented an Improved Stern and Steering Apparatus for River Steamers; and I do hereby declare the following to be a full and exact description of the same, reference being had to the accompanying drawing making part of this specification.

Figure 1 is an elevation and partial section of my improvement.

Figure 2, a perspective view of the same.

Figure 3, a plan of the metallic protecting-shoe.

Like letters designate corresponding parts in all the figures.

The object of this invention is to allow of steam-boats being landed by the stern without "rounding to," when headed down stream, in rivers with strong currents, thus effecting a great saving of time and expense in making landings on ordinary trips, and also, in case of fire or other accidents, to open a better avenue of escape for the passengers.

The landing of a boat, with the bow up stream, in making down trips, is well known to consume a large portion of valuable time, and it can be shown, by reports of recent disasters on our rivers, that a large percentage of the loss of life has been occasioned by the pilots not being able to land boats of ordinary construction by the stern.

In the usual manner of constructing boats, no "after-castle" is provided, and any attempt to "back in" to shore would inevitably crush the rudder if the bank was low or shelving, and both rudder and after-guard if the bank was high.

In the present invention I obviate all this by furnishing the boat with a complete "after-castle," provided with bits, chocks, capstan-lines, &c., and also a complete protection for the rudder.

Description.

In the drawing—

A is the hull, and

B the main deck, projecting beyond the hull to form a guard in the usual manner.

This deck projects out over the rudder at the stern, and is strengthened by a system of fan-tail splicing, F, built in with the hull, and planked over in a manner similar to that shown in the drawing.

The kelson *a* and stern post *b* of the vessel are framed together, and rest, at the point of junction, in a metallic protecting-shoe, C, where they are retained by means of bolts *e e e*, or other equivalent device. This arrangement is shown, enlarged, in fig. 3.

The shoe C is prolonged, to form a solid beak, into which is stepped the foot of the rudder-stock, the

blade D of the latter being cut away so as to overhang the beak of the shoe, as shown.

The rudder-stock has also a bearing in the strap *d*, which is attached to the stern-post, and carries on its upper end a horizontal sheave, E, around which the tiller-rope or chain *s* is rove two or more times, and then carried forward, in the usual manner, to the pilot-wheel.

The substitution of the sheave E in lieu of the ordinary tiller, enables the pilot to lay the rudder around against the side of the vessel out of danger, which he could not possibly do with a tiller.

Should the bank against which the boat is to land be low or shelving, the blade of the rudder is turned around out of the way, and the shoe C strikes the bank, thus protecting the rudder-stock from injury.

Should the bank be high, the main after-guard, which is so braced by the system of splicing F as to possess equal strength with the bow, or nearly so, will strike and effectually preserve the rudder from injury.

The judgment of the pilot must, of course, be exercised in landing, so that he may know whether it will be necessary to lay the rudder alongside or not, and, if necessary, to do so at the proper moment.

The tiller-sheave E and tiller-rope *s* are situated below the main deck B, out of the way, and safe from injury and obstruction.

It is to be understood that the arrangement of the several parts herein described is to be considered solely in relation to the purpose of this invention, namely, to so construct the stern of a steamboat that it can be landed, stern foremost, without injury to itself or to the rudder from striking the wharf or grounding, and so that the same facility for embarking and disembarking may be afforded, without hindrance or obstruction, as when landing at the bows, and I disclaim the arrangement, except as a whole, to effect this purpose.

What I claim as my invention, and desire to secure by Letters Patent, is—

The arrangement, as a whole, of the tiller-sheave E, under the main deck B, within and protected by the projecting stern-guard F, and the rudder D, protected beneath the said stern-guard, and overhanging the shoe C, when also, it is arranged to turn forward against the sides of the steamboat, so as then to be protected by the said shoe, as and for the purpose herein specified.

Witness my hand this 23d day of December, 1869.

DAVID DE HAVEN.
